OTIS A. MYGATT, OF NEW YORK, N. Y., ASSIGNOR TO HOLOPHANE GLASS COMPANY, OF NEW YORK, N. Y., A CORPORATION OF NEW JERSEY.

GLASS STRUCTURE.

1,152,953

Specification of Letters Patent.

Patented Oct. 26, 1915.

Application filed July 22, 1907. Serial No. 384,954.

To all whom it may concern:

Be it known that I, OTIS A. MYGATT, a citizen of the United States, and resident of the city and State of New York, have invented certain new and useful Improvements in Glass Structures, of which the following is a specification.

The object of my invention is to press or cut glassware so that the ribbed surface shall present alternating areas of high and low light, which appear to move upon the surface of the glassware as the observer changes his position.

Glassware made according to my invention is provided on both its outer and inner surface with ribbings following lines of direction which lie in planes containing the vertical axis of the inclosure. These I have called axial planes.

My invention consists in placing the corrugations on one side so as to be offset to those on the opposite side. This offset relation may be obtained either by using corrugations on one side unequal in width to those on the other, or by using corrugations of exactly the same width but not lying directly opposite. The preferred form of my invention is embodied in those inclosures in which the corrugations on one side are unequal in width to those on the other and in which the combined width of two or more ribs on one side does not evenly and exactly equal the width of the rib facing them on the opposite wall of the glass.

My invention is especially advantageous when used in connection with reflectors and shades for artificial lights, because such inclosures are used in combination with light sources which generally occupy the position and direction of the vertical axis of the inclosure. They are also usually placed above the plane of vision and are viewed from below. The eye of the observer, therefore, moving at right angles to the corrugations passes rapidly from one corrugation to the other and thereby secures the most sudden changes in light effect. With a horizontal construction, the eye of the observer would follow the length of the corrugations and no changes would be observed.

My invention will be more clearly understood by referring to the drawing, in which—

Figures 1, 2 and 3 are a top plan, an elevation and a bottom plan, respectively, of a dish or plaque embodying my invention; and in which Figs. 4, 5 and 6 are diagrammatic views illustrating the effect produced by my invention.

The dish or plaque illustrated in Figs. 1, 2 and 3 has reflecting prisms on the outside and lenticular ribbings on the inside thereof. It will be observed that while the figures made up of prisms and ribbings, respectively, are symmetrical, the ratio of the number of prisms to the number of lenticular ribs is nine to seven. The moving quality of the light hereinbefore referred to will be apparent in the areas where there are prisms 20 and ribbings 21 opposed to each other. On the other hand, at the center 22 where there are no prisms this effect will not be apparent.

In Figs. 4, 5 and 6 are shown diagrammatically sections of inclosures having upon the opposite faces thereof prisms extending longitudinally of the inclosure and substantially parallel with each other. Upon one side in each case there are 90° prisms, while, on the other side, there are substantially 110° prisms. In Fig. 4 the ratio of the number of prisms on one side to that on the other is three to two. In Fig. 5 this ratio is two to three. In Fig. 6 this ratio is four to three. For the sake of clearness the prisms are represented as being on a flat piece of glass, that is, on an inclosure having an infinite radius. The light is represented by parallel rays 23 striking in each case that side of the inclosure which has the 90° prisms thereon. Each of Figs. 4, 5 and 6 comprise a curve showing the intensity of the light distributed on a surface X—X parallel to the inclosure. The ordinates of each of these curves are calculated by the number of lines per half centimeter which strikes surface X—X.

The curve in Fig. 4 is divided into sections A—B, B—C, etc., corresponding to the faces of the 90° prisms. The rays 23 striking one face of a 90° prism are refracted and upon their emergence from the faces of the 110° prisms on the other side encounter rays which originally struck the other face of the 90° prism. As shown by the curve, the intensity of light upon the

surface X—X will vary so that the curve comprised by the sections A—B and B—C will be symmetrical with that comprised by the sections C—D and D—E.

5 In Fig. 5 the sections of the curve are A—B to F—G, inclusive. The ratio of two to three between the numbers of prisms on each side produces a curve which differs from that of Fig. 4, but sections of which 10 are still symmetrical.

In Fig. 6 the sections of the curve are indicated as A—B to F—G, inclusive. The ratio of four to three between the number of prisms on each side of the inclosure produces a distribution of still another character upon the surface X—X.

It will be apparent from the drawing that high and low light areas are produced where radial corrugations on one side are opposite 20 to parallel radial corrugations on the opposite side. It will be found that when ribs of equal width are placed directly opposite each other no bands of high and low light areas are observed. As the eye passes over 25 such a surface the variations in the intensity of the light are symmetrical, being exactly the same for the extent of each prism and, therefore, no movable or changeable effect is observed.

30 By the term "inclosure" I intend to differentiate from flat bodies and to indicate bodies having walls extending more or less in the general direction of an axis, so that prisms may be formed upon said walls

which can be said to have a longitudinal extension.

I claim:

1. Glass inclosures having a series of adjacent longitudinal ribs upon one side and upon the other side also a series of adjacent longitudinal ribs substantially parallel thereto, the ribs on the one side being offset with respect to those directly opposite them on the other side.

2. Glass inclosures having a series of adjacent longitudinal prisms upon one side and upon the other side a series of adjacent longitudinal ribs substantially parallel thereto, the prisms on the one side being offset with respect to the ribs on the opposite side.

3. Glass inclosures having a series of adjacent longitudinal double reflecting prisms on the one side and on the other side adjacent longitudinal ribs substantially parallel thereto, the prisms on the one side being offset with respect to the ribs on the opposite side.

4. Glass inclosures having a series of adjacent longitudinal prisms on the one side and on the other side also a series of adjacent longitudinal prisms substantially parallel thereto, the prisms on the one side being offset with respect to those on the opposite side.

OTIS A. MYGATT.
